UNITED STATES PATENT OFFICE.

CHARLES E. CLEVELAND, OF FOND DU LAC, WISCONSIN.

LOG-TURNER.

SPECIFICATION forming part of Letters Patent No. 743,247, dated November 3, 1903.

Application filed February 3, 1902. Serial No. 92,276. (No model.)

To all whom it may concern:

Be it known that I, CHARLES E. CLEVELAND, residing at Fond du Lac, in the county of Fond du Lac and State of Wisconsin, have 5 invented a new and useful Improvement in Log-Turners, of which the following is a description, reference being had to the accompanying drawings, which are a part of this specification.

10 The object of my invention is to provide means whereby the so-called "oscillating-cylinder" log-turners, illustrated in Patent No. 245,496, granted to William E. Hill, can be readily transformed into practically a stationary-cylinder log-turner, and thereby do away with the objectionable radius-bar P, which oscillates the cylinders to so large extent that it becomes a continual nuisance to keep the steam connections in proper condition; 15 furthermore, to provide a more substantial and improved construction in log-turners than has heretofore been in use.

Heretofore log-turners have consisted of either two oscillating cylinders or two stationary cylinders; but never before to my knowledge has one stationary and one oscillating cylinder been used for imparting the various movements to the tooth-bar.

20 My invention consists of the tooth-bar and combination of the stationary cylinder and oscillating cylinder, as herein described and claimed, or the equivalents thereof.

In the drawings, Figure 1 represents a side elevation of a log-turner embodying my improvements. The operating-levers and connections are omitted as not being essential in describing my invention. Fig. 2 is a longitudinal section of the slides No. 5, as indicated. Fig. 3 is a view of the connection of the tooth-bar and piston-rod of the stationary cylinder forming a cross-head to work in the above-mentioned slides.

I will now proceed to describe a construction in which I have carried out my invention in a practical way and will then particularly point out in the claims those features which I deem to be new and desire to secure by Letters Patent.

In the drawings, 2 represents an ordinary 50 tooth-bar, such as is generally used for the purpose, the lower ends of which are con-

nected in a suitable manner to the piston-rods of cylinders 3 and 4. The cylinder 3 is provided with trunnions 12 on its lower end in order to allow the said cylinder to oscillate 55 when top of tooth-bar is forced back. The cylinder 4 is made stationary by means of the slides 5, which are suitably fastened to framework of mill. The upper end of piston-rod 7 I have provided, as shown in Fig. 3. 60 The pin 6 $\frac{1}{2}$, which connects the said rod with the tooth-bar, is made long enough to form a bearing for the rollers 6. The rollers 6 fit loosely into the groove 9 of the slides 5.

Number 14 represents the ordinary floor- 65 plate, which is for the purpose of limiting the lateral movement of the tooth-bar.

Both cylinders being provided with the ordinary valves and connections for operating same, it is at once apparent that when pressure is applied to cylinder 3 the top of the tooth-bar will be forced backward and behind the log which is to be forced onto the carriage 1. Now if pressure is applied to cylinder 4 the tooth-bar will be forced upward and at the same time forward, thus forcing the said log onto the carriage. If the log is to be turned or rotated while on the carriage, a vertical movement is required of the tooth-bar, and this movement is imparted by 75 admitting pressure to cylinder 4 only or to both cylinders simultaneously.

Having thus described my invention, what I claim as new, and desire to secure by Letters Patent, is—

1. In a log-turner, the combination of a fixed cylinder, and its piston-rod; a pivoted cylinder, and its piston-rod; and a toothed bar directly pivoted to said rods, substantially as described.

2. In a log-turner, the combination of a fixed cylinder, and its piston-rod; a guide in line with said rod; a pivoted cylinder, and its rod; and a toothed bar the base of which is pivotally connected at its opposite ends directly to said rods, substantially as described.

In testimony whereof I affix my signature in presence of two witnesses.

CHAS. E. CLEVELAND.
